VENDING MACHINE

Ralph R. Westfall, Los Angeles, Calif., assignor
to American Coin Machine Company, Los
Angeles, Calif., a corporation of California

Application September 24, 1934, Serial No. 745,315

3 Claims. (Cl. 194—75)

This invention relates to vending machines.

An object of the invention is the provision of a vending machine adapted to be operated by a coin which when of the right type will be positioned so that when a manually-operated lever is actuated the coin will engage a package and move the same from the magazine to be discharged through an open-ended chute.

Another object of the invention is the provision of a vending machine which is coin-controlled and which has provision for throwing out slugs to prevent the slug from releasing packages in a magazine when a manual lever is operated.

A further object of the invention is the provision of a vending machine having a slot to receive a coin with a guide for directing the coin upon an abutment attached to a manually operated lever, the guide also including means for directing slugs away from the abutment so that the slugs will be discharged through an opening to the exterior of the housing, the coin being supported by the abutment in position to engage the lowermost package in the magazine and acting as a positive means for removing the package so that it will be discharged to the exterior of the housing when the lever is actuated.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Figure 1 is a vertical section of the vending machine taken along the line 1—1 of Figure 2.

Figure 2 is a vertical section taken along the line 2—2 of Figure 1.

Figure 3 is a horizontal section taken along the line 3—3 of Figure 2.

Figure 4 is a fragmentary view in perspective of the lower end of a magazine for storing articles to be vended.

Figure 5 is a view in perspective of a removable guide for coins.

Figure 6 is a view in perspective of a manually-operated means for causing the coins to remove the article from a magazine, and

Figure 7 is a view in perspective of a modified form of the slot and coin-receiving member.

Referring more particularly to the drawings, 10 designates the bottom of a housing which is preferably formed of metal. The housing also in-

cludes a front wall 11, a rear wall 12, and side walls 13 and 14.

A cover 15 is hinged at 16 and is provided with a flange 17 adapted to engage over the upper end of the front wall 11. A hasp 18 is secured at 19 to the front wall and projects through a slot in the usual manner in the flange 17. A lock 20 is adapted to be received by the hasp.

A partition, generally designated by the numeral 25, has its longer portion in flat engagement 10 with the rear wall 12. The upper end of the partition, as shown at 26, is curved inwardly and terminates adjacent one wall of the magazine 27. The lower end of the partition adjacent the bottom 10 is curved forwardly, as shown at 28, and 15 then inclined downwardly towards the front end of the bottom where it is received by a flange 29 formed integrally with said bottom.

The front wall 11 is provided with an opening 30 adjacent the lower end so that articles dispensed from the magazine 27 may be removed from the housing after they have been discharged towards the opening by the inclined portion 31 of the partition.

The magazine 27 is provided with two compartments 32 and 33. Each compartment has side walls 34 and 35 formed of metal with the end of the side walls, as shown at 36 and 37, inturned sufficiently to engage the packages 38 for retaining the packages in superimposed relation. The 30 side walls 35 of each compartment, as shown in Fig. 3 are in flat contact with each other and may be secured together in any approved manner. The outer side walls 34 are connected to the side walls 13 and 14 of the housing. 35

Brackets 40 have an upwardly extending flange 41 which is secured to the flanges 36^a of the walls 35 of the magazine 27. The downturned flanges 42 of the brackets are secured to the front and rear walls as shown in Fig. 1. These brackets 40 support the upper end of the magazine centrally of the housing.

The lower ends of the walls 34 and 35 are provided with inturned flanges 43 which are adapted to support the lowermost package 38 and these flanges terminate short of the width of the walls 34 and 35 so that when they are moved forwardly towards the open end 44 of the compartments, they will be released from the magazine and dropped to the inclined portion 35 of the partition 25. It 50 will be noted that the lower ends of the flanges 36 and 36^a are cut away adjacent the lower portion sufficiently to permit the discharge of a package from a compartment, as shown at 45.

The bottom of the magazine, as shown more 55

particularly in Figs. 1 and 2, is supported upon brackets 46 which have vertical walls 47 secured to the side walls 13 and 14 and depending flanges 48 spaced from the side walls for a purpose which will be presently explained.

A shaft 50 is provided with journals, as shown at 51, in the members 47 and the side walls 13 and 14. Substantially 90° segments 52 are secured to the shaft 50 in spaced relation and are in the form of blocks which have a curved outer face 53. An edge of each of these blocks is flat, as shown at 54, to receive and support a coin 55.

Each of these blocks is provided with a triangularly-shaped lug 56 which has an inclined coin-engaging face 57 adjacent the flat face 54 of each block. As shown more particularly in Fig. 6 the lugs 56 and 56^a are formed integrally with the blocks and with the shaft 50. The lug 56^a is oppositely disposed to the lug 56. A leaf 54^a is secured to each lug and spaced from the flat face 54 to provide a pocket for a coin.

A handle 60 is rigidly secured to the shaft 50 and is provided with a notch 61 adapted to be received by a pin 62 secured to one of the members 47 in the side wall 14. The pin 62 supports the arm 60 in an inoperative position. Said arm projects beyond the housing and moves through a slot 65 formed in the front wall 11.

A coin chute is shown more clearly in Fig. 5 and comprises an inclined wall 66 and a wall 67 inclined substantially at right angles to the wall 66. Ears 68 are formed integrally with the walls 67 and are secured at 69 to the side walls 13 and 14 of the housing. The right angular portion 70 of the combined walls 66 and 67 project through an opening in the front wall 11 where the wall 67 is provided with a pair of slots 71 to receive the coin. The wall 66 is provided with an opening generally designated by the numeral 72 into which project lugs 73. The opening at its lower end is partially defined by inwardly projecting arms 74 formed from the material of the wall 66. A pair of flanges 75 extend upwardly from the plate 66 and at the lower ends of the openings 72.

A magnet 76 is secured to the plate 66 and between the coin slots 71. A coin receptacle, generally designated by the numeral 80, is provided with a rib at each side thereof adapted to be received by a track 82 secured to the side walls 13 and 14. Thus it will be seen that the receptacle 80 may be moved towards the front or rear of the housing. Projections 83 are formed on the front wall 84 of the receptacle 80 and are adapted to engage the front wall 11 of the housing for spacing the front wall of the receptacle from the inner face of the front wall of said housing in order to permit slugs to pass downwardly along the front wall 11 of the housing and to be discharged adjacent the opening 30.

The upper end of the receptacle 80 has an inclined front wall 85 and a rear inclined wall 86, thereby reducing the opening at the upper end of a receptacle which is adapted to receive a coin after the package has been discharged from the inclined portion 31 of the partition 25.

The operation of my device is as follows: When a coin of proper denomination is placed in one of the slots 71 it will pass over a lug 73 and be guided by a flange 75 across an arm or bar 74 and thence onto the flat face 54 of a block 52. A portion of the periphery of the coin will rest upon the inclined surface 57 of either the lug 56 or 56^a as the case may be and a portion of the periphery will engage the depending flange 48 on the bracket 46, thereby retaining the coin in an operative

position as shown in Figs. 1 and 2 and adapted to engage a package 38 in the magazine 27 when the arm 60 is operated.

The arm 60 is then elevated and moves through the slot 65 whence the shaft 50 will be rocked as will a block 52 and the coin 55 will be moved by the flat face 54 of the block. Due to the engagement with the lowermost package 38 in one of the compartments of the magazine 27 the coin will force the package outwardly through the open lower portion of the compartment of a magazine until the package will fall by gravity off the flanges 43 and be deposited upon the inclined surface 31 whence it will move towards the opening 30 of the front wall 11.

When a slug is placed in the slot 71 instead of a coin, the slug will be attracted by the magnet 76 and be moved away from the lug 73 towards the center of the opening 72. The slug will then fall centrally of the openings 72 instead of moving downwardly on to the flat face 54 of one of the blocks 52. As the slug falls from the plate it will drop downwardly towards the inclined face 85 of the receptacle 80 and pass through the space 90 located between the front wall 11 and the front wall 84 of the receptacle 80 and be deposited adjacent the opening 30 at the front end of the housing.

Thus it will be seen that when a coin of proper denomination is placed in a slot 71 and the handle 60 is operated the coin will act as a positive means for forcing the package 38 from the magazine 27. On the other hand if it be attempted to operate the machine by a slug, the slug will be discharged from the device and the package will remain un-moved within the magazine.

The inner edges of the flanges 48 terminate substantially short of the vertical position of the coin and this position is reached when the article has been moved out of the magazine. At this point the coin is released by the flange and the inclined edge 57 of a lug 56 or 56^a causes the coin to roll from its retained position and be discharged into the receptacle 80.

When a token or slug having a central opening is placed in the device the lug 73 will enter said opening and thus tilt the token or slug so that the token will fall through the opening 72 and into the delivery chute.

A modified form of the slide and coin-receiving device is shown in Fig. 7. This slide comprises a flat plate 91 having a pair of openings 92 intermediate its ends and an angularly disposed plate 93 with perforated attaching flanges 94. The plate 93 is provided with spaced slots 95 to receive coins which will slide over the member 91. The plate is provided with V-shaped lugs 96 projecting into the openings 92 for a purpose which will be presently explained.

A magnet 97 is located on the portion of the plate between the openings 92 and is adapted to draw slugs towards the magnet so that they will slide upon the portion 98 of the plate and then drop vertically downwardly to one side of the coin receptacle 80.

At each outer side of the openings 92 is provided a flange 99 adapted to aid in guiding legitimate coins along a straight line.

Depending from the plate 91 are attaching flanges 100 and these attaching flanges are supported by means of inclined flanges 101 projecting inwardly from the plate 91. Inclined at an angle from the inner edges of the flanges 101 are flanges 102 which are adapted to engage a 75

coin for a purpose which will be presently explained.

A shaft 103 has pintles 104 rotatably mounted in openings 105 in the flanges 100. An operating handle 106 is rigidly connected with a shaft 103 and is adapted to be operated in the same manner as the handle 60 shown in Fig. 1.

Connected to the shaft 103 or integrally formed therewith is a flat plate 110 which is rockable with the shaft. This plate normally is disposed in a plane which is offset from the plane of the plate 91. A lug 111 depends from the plate 91 and is offset therefrom to normally maintain the plate 110 in position.

15 A second plate 112 is secured to the intermediate portion of the plate 110 and has its ends spaced from the ends of the plate 110, as shown at 113. This space is sufficient to receive a coin as shown in dotted lines. An intermediate portion 114 of 20 the plate 112 has its outer surface in the same plane with the adjacent surface of the plate 91 and forms a track for a slug which has been drawn away from the normal path by the magnet 97. The bowed portion 115 of the members 113 forms a side wall which is engaged by the coin.

25 The operation of this construction is as follows: When a legitimate coin is placed in one of the slots 95 it will slide downwardly over the lug 95 and be guided by the flange 91 until it is received within the pocket between the ends of the plate 110 and the bowed-out ends 113 of the plate 112. In this position the coin is engaged by the portion 115 of the plate 112 and the edge of the flange 102 and the coin will remain in this position until the handle 106 is rocked sufficiently to move the coin off the outer end of the flange 102. During this movement, however, the coin will engage the package in the same manner as shown in Fig. 1 and move the package from the magazine.

40 Directly after the package has been removed the coin will have been moved away from the outer end of the flange 102 so that it will drop through the spaced plates 110 and 112 and then fall into the receptacle 80.

45 If a token or other circular device is placed into the slots 95 and these tokens have a central opening this opening will be aligned with the V-shaped lug 96 and the lug will cause the token to be revolved slightly on the lug and it will fall through the opening 92.

50 If on the other hand a slug is placed into a slot 95 it will be attracted by the magnet 97 and will move away from the opening 92 and travel downwardly over the portion 93 of the plate 91 and then over the portion 114 of the plate 112 and be discharged to one side of the receptacle. Thus it will be seen that when a token having a central opening or a slug is placed in the device the token or slug will be deposited into the space through which the article ordinarily is discharged and which can be removed through the opening 30.

It must be borne in mind that since the token or slug will not fall into one of the pockets between the plates 110 and 112 the token or slug cannot be utilized for moving the package from the magazine.

5

I claim:

1. A vending machine comprising a housing, a rock shaft in the housing having a flat surface which will aid in guiding a coin along a definite path, a block secured to said shaft and provided with a flat face in alignment with the flat surface, the flat face being inclined to the horizontal and providing a support upon which the coin will lie, a lug secured to the block and having an inclined face, means for rockably supporting the shaft in the housing and having means engageable with the coin and cooperating with the inclined face of the lug for retaining the coin against said flat face during a predetermined rocking angle of the shaft, means for supporting in a horizontal plane, a package to be dispensed, said coin when retained by the block adapted to engage an end of the package and force the package clear of the horizontal package supporting means when the shaft is rocked.

25

2. A vending machine comprising a housing, a rock shaft in the housing, a U-shaped member projecting laterally from the shaft adapted to receive a coin and be retained at an acute angle to a horizontal when the shaft is normally at rest, 30 a lug having an inclined face located within the U-shaped member, said lug and a leg of the U-shaped member being substantially parallel to the shaft, means for rockably supporting the shaft in the housing, said means including means 35 engageable with the coin and cooperating with the inclined face of the lug for retaining the coin in the U-shaped member so that the projecting portion of the coin will be in a position to engage one end of a package to be dispensed, a discharge 40 chute, a supporting means for said package disposed in a horizontal plane, said coin when the shaft is rocked forcing the package off the supporting means into the discharge chute.

35

3. A vending machine comprising a housing, 45 a rock shaft in the housing and provided with a flat face against which the coin is adapted to lie, a leaf connected to the shaft in spaced relation with the flat face of the shaft, means for supporting the shaft and provided with an extension 50 adapted to engage the coin and retain said coin between the leaf and flat face with the coin projecting beyond the leaf until the shaft is rocked sufficiently to release the coin from the extension, a discharge chute, means for supporting an article 55 to be dispensed in a horizontal position and across the path of the moving coin so that when the shaft is rocked the article will be dislodged by the coin and forced into a falling path to enter the chute.

60

RALPH R. WESTFALL.
